UNITED STATES PATENT OFFICE.

HARRISON H. TAYLOR, OF DETROIT, MICHIGAN, ASSIGNOR TO FREDERICK A. HUBEL, OF SAME PLACE.

CAPSULE-CUTTING MACHINE.

SPECIFICATION forming part of Letters Patent No. 268,961, dated December 12, 1882.

Application filed April 13, 1882. (No model.)

To all whom it may concern:

Be it known that I, HARRISON H. TAYLOR, of Detroit, in the county of Wayne and State of Michigan, have invented new and useful Improvements in Capsule-Cutting Machines; and I hereby declare that the following is a full, clear, and exact description thereof, reference being had to the accompanying drawings, which form a part of this specification.

10 The nature of this invention relates to certain new and useful improvements in the construction of machines for cutting off gelatine capsules; and the invention consists, first, in the mode of cutting off the capsules by means of laterally-moving knives, in combination with loose forming-pins; and, second, in the peculiar construction and arrangement of parts, all as more fully hereinafter set forth.

Figure 1 is a front or end elevation of my 20 machine. Fig. 2 is a vertical central cross-section. Fig. 3 is a side elevation. Fig. 4 is a top plan, with part of the follower broken away so as to disclose portions of the underlying parts. Fig. 5 is a detached perspective 25 of a portion of a knife secured to its shaft.

In the accompanying drawings, A represents the bed-plate, to which is attached the vertical plate-standard B, the outer ends, a, of which form guides for the follower C. This 30 follower consists of the vertical portion b and the horizontal and overhanging part c. To the under side of the latter the mold-plate D is removably secured in any convenient manner. The mold-plate D carries, as usual, a series of pins, E, upon which the gelatine capsules were 35 previously formed in the usual manner. For the proper operation of my machine, I use pins which are loosely set into the mold-plate, so as to be able to rotate upon their axis, and the 40 pins E shown in the drawings are of that description.

On top of the bed A, and journaled in bearings d d at each end thereof, are the shafts F' F⁴. These shafts are provided at the front end 45 of the machine with the intermeshing and like pinions, G' G⁴, while their rear ends are provided with the circular racks H' H⁴. At the rear end of the machine, and journaled in proper bearings e e upon the bed, are the cross-shafts I 50 I'. Upon the outer ends of these shafts are the

two intermeshing pinions K K'. The shaft I is provided upon one end with a crank-handle, L, by means of which it can be rotated, and it has also secured upon it the pinions M' M⁴, which engage respectively with the racks H' H⁴. The shaft I has secured upon it the double 55 pinion M² M³, which engages with the racks H² H³.

N N are two levers, fulcrumed at f f to the standard B. Their outer ends are provided 60 with pins g g, which engage with the under side of the follower near the outer ends thereof. The follower-plate C is free to slide up or down upon the standard B, and its whole weight therefore rests upon the pins g, imparting to 65 the levers N a tendency to rise at their inner ends.

O is a sliding block held in the vertical slot P in the standard, and it is provided with the projecting ledge i, and a pin, h, which latter 70 engages in the slots k in the inner ends of the levers N N.

Q is another sliding block held in the slot P of the standard, and it is provided with the ears l l, between which the cam-lever R is ful-crumed. 75

S is a stop-screw entering from the top of the standard, with its lower end impinging upon the sliding block Q.

Each of the four shafts F' F⁴ has secured to 80 it, in any convenient manner, the knife-blade T. Its upper end is bent at right angles, and is properly grooved to form a cutting-edge. Parallel slits m subdivide the blade T into individual knives U, whose cutting-edge is a 85 little longer than one-half of the circumference of the former-pins E.

V is a lever attached to the front end of the shaft F⁴, and W is a segment provided with notches n n, with which the lever V is adapted 90 to engage.

In practice the mold-plate D, upon whose pins E the gelatine capsules are formed, is secured to the under side of the overhanging part c of the follower, and to allow this to be done 95 without interfering with the knives U the latter have to be in the position shown in dotted lines in Fig. 1, which position is obtained by engaging the lever V into the lower notch n of the segment W. After the mold-plate is put 100

in its prescribed position and locked therein the lever V is disengaged from the lower notch *n* and engaged with the upper one. This movement, by means of the intermeshing pinions 5 *g' g⁴*, rotates the shafts F' F⁴ in such manner that the knives U on the shafts F' F² converge and press with their cutting-edges against one row of pins E, while the knives U upon the shafts F³ F⁴ converge and press with their 10 cutting-edges against the second row of pins E. Their relative position toward the pins at this stage of the operation is clearly shown in Fig. 4, where the pins are shown in dotted outlines. Now, the crank L is taken hold of by 15 the operator and turned from its position shown in Fig. 4 and in dotted outlines in Fig. 3 to the position shown in Fig. 3 in full lines. This movement, by means of the different pinions and engaging racks described, pushes the 20 shafts F' and F⁴ one way and the shafts F² F³ the opposite way, and the pins E, being loose in their sockets, will therefore be rotated upon their axis by the movement of the cutting-edges of the knives U, this rotation being made 25 of sufficient duration to allow the knives to cut the capsules entirely around the pins. The operator now seizes the cam-lever R, which is in the position shown in Fig. 1, and raises it up into the position shown in Fig. 2, 30 and brings it back again to its old position. This movement drops the follower C a little distance, allowing the knives U to push and break off the separated portions of the capsules, thereby freeing the latter from the cut- 35 tings. The operator now engages the lever V again into the lower notch, *n*, which movement diverges the knives from the pins and allows the mold-plate to be withdrawn. As the whole weight of the follower C is supported

upon the ends of the levers N, the sliding 40 blocks O and Q have a tendency to rise in the slot P of the standard, and the set-screw will therefore adjust the follower C to any desired position.

Although I prefer to rotate the pins E by 45 moving the knives on both sides of the pins, it is obvious that one set of knives might be stationary and the other moved laterally a proper length to cut around the pins.

What I claim as my invention is—

1. The method of cutting off gelatine capsules by moving the knife or knives laterally, the former-pins being set loosely in the mold-plate and adapted to be rotated upon their axis by the movement of the knife or knives, 55 substantially as set forth.

2. In a cutting-off machine for gelatine capsules, the cam-lever R, in combination with the sliding blocks O and Q and levers N, for raising the mold-carrying frame, substantially as and 60 for the purposes specified.

3. In a cutting-off machine, a series of parallelshafts provided with intermeshing pinions for simultaneously rotating the same in alternating directions, and, in combination therewith, the knife-blades T, secured thereto and actuated thereby, substantially as set forth. 65

4. In a capsule-cutting machine, the combination of the devices for laterally moving the shafts F' F⁴, consisting of the shafts I I', pinions K K', and pinions M' M⁴, the latter engaging with the racks H' H⁴, constructed, arranged, and operating substantially as and 70 for the purposes specified.

HARRISON H. TAYLOR.
